SLIDER FOR SEPARABLE FASTENERS

Robert C. Legat, New Britain, Conn., assignor to
The G. E. Prentice Mfg. Co., New Britain, Conn.,
a corporation of Connecticut

Application August 30, 1939, Serial No. 292,550

3 Claims. (Cl. 24—205)

This invention relates to sliders for separable fasteners and has for its object the provision of a slider which will stay in the position in which it is brought to rest on the fastener and will not shift in the opening direction when the fabric tapes or stringers of the fastener are subjected to a lateral pull tending to spread them apart at their free ends or in the locality of the slider beyond the point where the interlocking elements of the fastener are interlocked.

The usual slider for a separable fastener of the slide operated type comprises a pair of spaced plates which are widened at one end and are connected at the center of the widened end by a substantially triangularly-shaped member which is positioned between such plates. The side edges of the plates are provided with short opposed guide flanges which together with the triangularly-shaped member form a Y-shaped channel between the plates for receiving the interlocking elements as the slider is moved longitudinally of the fastener. When the slider is moved in the closing direction, the elements of the stringers enter the two angularly-disposed arms of the Y-shaped channel and are guided into interlocking relation as they pass from such arms of the channel into the central leg thereof at the narrow portion of the slider. Conversely when the slider is moved in the opposite or opening direction, the elements are caused to become unlocked as they pass from the central leg of the channel into the angularly disposed arms thereof. It is a well known fact that a slider of this type can also be moved in the opening direction by a lateral pull on the disengaged portions of the stringers above the slider. This is probably due to the fact that the sliders heretofore made have been so designed that when the stringers are spread under a lateral pull, the rear ends of the elements are enabled to engage the interior surfaces of the portions of the flanges forming the arms of the Y-shaped channel and thereby to exert a camming action on such portions such as to force the slider in the opening direction. To overcome this tendency of a slider to move in the opening direction when the stringers are under stress, various locking means have been devised, such as, movable detents which are either actuated manually or by spring members or by gravity and rigid detents which are formed on the slider body so that they come into interlocking engagement with the elements when the latter are displaced from their normal paths of movement by the laterally applied forces. The provision of these detents, however, necessitates

additional manufacturing operations and/or additional parts thereby increasing the cost of manufacture of the ordinary standard type of slider. Furthermore the rigid type of detent has with the exception of a few cases proven unsatisfactory because while it prevents the free movement of the slider in the opening direction under the application of lateral forces, it does not prevent the slider from creeping in such direction during usage of the fastener and wears off or becomes ineffective in time because of the frictional engagement of the interlocking elements in their passage through the slider.

In the slider of this invention there are no additional means such as has heretofore been provided for preventing the unintended, self-actuated movement of the slider but the several parts which constitute the basic form of the slider are so designed that the slider will become automatically and reliably locked against movement in the opening direction under lateral forces applied to the stringers above the slider. A better understanding of the invention as well as the novel details of construction thereof will be obtained from the following description when read in connection with the accompanying drawing in which Fig. 1 is a plan view of a portion of a separable fastener provided with a slider embodying the invention, the slider being shown in longitudinal section and the stringers of the fastener being unstrained so that the elements attached thereto pursue their normal paths of movement through the slider; Fig. 2 is a central longitudinal sectional view of the slider shown in Fig. 1, Fig. 3 is a view similar to Fig. 1 showing the relative positions of the elements within the slider under lateral stresses applied to the portions of the stringers above the slider; Fig. 4 is a side view of the slider illustrated in Figs. 1 to 3; Fig. 5 is a plan view of a portion of a separable fastener provided with a modified form of slider made in accordance with the invention and Fig. 6 is a central longitudinal sectional view of the slider shown in Fig. 5.

In the several views of the drawing, the reference characters 10 and 11 designate the stringers of the fastener structure which are usually constituted of fabric and are reinforced along their opened edges to provide a satisfactory grip for the rows of interlocking elements 12 and 13 clamped to such edges. As is customary, the elements of each row are staggered with relation to the elements in the other row so that the elements of both rows may be successively brought together and progressively interlocked by means

of a slider which, in Figs. 1 to 4, is generally designated by the numeral 14. Also as is customary, the slider 14 in Figs. 1 to 4 comprises a pair of spaced top and bottom wings or plates 15 and 16, respectively, connected by an integral wedging and spacing member 17 of substantially triangular shape in the region between the plates 15 and 16. The member 17 projects through an opening in the top plate 15 and extends rearwardly of the slider to form a lug 18 to which is connected a pull member 19 which is manually actuated to move the slider longitudinally of the fastener along the rows of elements. The lateral edges of the slider wings 15 and 16 are bent inwardly to provide the guide flanges 20 and 21 on opposite sides of the slider and these flanges form together with the wedging portion 17, a channel having diverging arm portions 22 and 23 and a central leg portion 24 positioned at the narrow end of the slider and connected with the inner ends of the diverging arm portions 22 and 23. The portions 25 of the flanges 20 and 21 which form the leg portion 24 of the channel are disposed in substantially parallel relation and extend from the narrow end of the slider towards the widened or front end thereof to the points 27 a distance of approximately one-third the longitudinal length of the slider. From the points 27 which are below the pointed end or apex of the triangularly-shaped separating or spacing member 17, the flanges 20 and 21 diverge outwardly to provide the portions 26 in the body of the slider which form the outer sides of the diverging arm portions 22 and 23 of the channel.

In accordance with the invention, the portions 26 of the flanges 20 and 21, which at the points 27 are spaced apart a distance substantially equal to the widths of the two rows of elements 12 and 13, in the latter's interlocked condition, bend outwardly and upwardly in opposite directions from such points 27 to terminate at their outer ends at points 28 which are positioned substantially in line with the outer ends of the side camming surfaces of the triangularly-shaped member 17. Throughout its entire length each flange portion 26 is spaced from the member 17 a sufficient distance to enable the elements to pass therebetween with ease and is preferably formed so that the inner half thereof, i. e., that half which starts from the point 27, is arcuately-shaped while the forward half thereof in the region of the longitudinal portion of the slider occupied by the separating member 17, is straight and in parallelism with the portion 25 of the flange of which it forms a part. Intermediate the angularly-disposed side camming face of the member 17 and the flange portion 26 the space is substantially greater than the length of an interlocking element while between the straight longitudinally extending side camming face at the forward or outer end of the member 17 and the part of the straight section of the flange portion 26 opposing such face and at the outer end of such flange portion 26, at the point 28, the width of the channel is only slightly greater than the length of an interlocking element. The form of the flange portions 26 is such that a straight line 29-29 (see Fig. 2) drawn from the point 27 of one flange to the point 28 at the outer end thereof, will not intersect or cross any intermediate part of the interior surface of such portion 26 and is so disposed with respect to the member 17, that the space between such line and the apex 30 and a portion of the side camming surface of the member 17 is less than the length of the

elements attached to the stringers. Thus any lateral force applied to a stringer above the slider tending to straighten the portion thereof between the points 27 and 28 will move the outer interlocking ends of the elements into engagement with the triangularly-shaped separating member 17.

It will now be observed from Fig. 1 of the drawing, that during normal operation of the fastener the rows of fastener elements 12 and 13 enter into the spaces between the separating member 17 and the portions 26 of the flanges forming the diverging arms of the channel at the wide end of the slider, as the slider is moved toward the unlocked portions of the fastener, and are brought together and guided into interlocked engagement as they pass into the leg portion of the channel in the narrow part of the slider towards the open end. Movement of the slider in the opposite direction causes the flexible material of the stringers to which the interlocked fastener elements are attached to give way and to be bent laterally separating the interlocking portions of the locked fastener elements and permitting the fastener elements of each of the two stringers to pass through the arms of the channel on opposite sides of the separating member 17. During these movements of the slider in either the opening or closing directions the passage of the elements through the channels is in no way interfered with, the diverging arms of the channel being sufficiently wide to allow the elements to pass therethrough freely and permitting free movement of the slider with relation to such elements. Now assuming the fastener to be closed or in a partially closed condition and a lateral pull applied to the stringers above the slider, the lateral forces exerted on the stringers will cause the portions of the reinforced edges thereof within the slider and between the points 27 and 28, to tend to straighten out, thereby moving the interlocking ends of the fastener elements carried on such portions into engagement with the separating member 17. The straightening of the portions of the reinforced edges of the stringers between the points 27 and 28 will under the applied lateral forces jam the interlocking ends of the elements against the angularly-disposed side camming faces of the member 17 and the end of at least one of the elements will engage in a jamming relationship with the apex of the member 17 as is shown in Fig. 3. This jamming action is carried down into the leg 24 of the channel by the engaged ends of the elements so that any movement of such elements toward the diverging arms 22 and 23 of the channel is obstructed, thereby preventing movement of the slider in the opening direction or toward the interlocked portion of the fastener. The greater the lateral force that is exerted on the stringers tending to separate them, the more securely and positively will the slider be locked or obstructed against movement in the opening direction.

It will be seen from the foregoing that the portions of the flanges forming the diverging arms of the channel are formed so as to permit the slider to be shifted in either direction by a force applied to the pull in a longitudinal direction during the normal operation of the slider, the fastener elements being simply cammed by the separating member 17 into the arm portions of the channel which are sufficiently wide to permit of free movement of the elements through such portions of the channel. On the

other hand the flanges in the region of such arm portions of the channel are so designed that when a lateral pull is applied to the stringers above the slider the latter will be effectively locked against movement and the greater the strain on the stringers the more positive will be the locking effect.

It will be evident from the foregoing that this invention provides a very simple and effective locking means which does not require the addition of locking detents of any sort, which requires no change in the methods and machines now used for making fastener sliders and which can be made at no extra cost to the manufacturer.

While I have hereinabove specifically described the preferred embodiment which my invention may assume in practice, it will be understood that this embodiment is merely for the purposes of illustration and description and that various other forms and/or modifications may be devised which do not depart from the spirit and scope of my invention. For example, instead of forming the slider as is illustrated in Figs. 1 to 4, the slider 15 may be constructed in the manner illustrated in Figs. 5 and 6. In this embodiment of the invention, there are two separate plates which are similar in form and which are provided on their interior surfaces with Y-shaped grooves which 20 form the channel for the interlocking elements of the separable fastener. As is shown in Fig. 6, the groove in the interior surface of each plate is formed so that the spaced arms 35 and 36 thereof sweep into the central leg 31 thereby eliminating 25 any sharply defined shoulders, as at the points 27 in the embodiment illustrated in Figs. 1 to 4 of the drawing, and forming a boat-shaped central portion 38. In the assembled condition of the 30 plates, the central portions 38 thereof engage one another and together form a separating member adapted to disengage the interlocking elements 35 when the slider is moved in the opening direction on the fastener. The edge portions 39 and 40 of the plates are slightly lower than the central 35 portions 38 thereof so that in the assembled condition of the parts such edge portions are spaced sufficiently to enable the fabric of the stringers to 40 pass freely therebetween in the movements of the slider. The plates are secured together by a rivet 41 which passes through the central portions 38 of both plates and is provided at one end with a circular head 42 which is spaced from the outer 45 surface of the adjacent plate. Rotatably mounted on the rivet 41 intermediate the head 42 and the 50 adjacent plate is a swivel member 43 to which is attached a pull chain 44. Movement of the plates relative to each other about the rivet 41 is prevented by any suitable means as by a rivet 45 which extends through the outer ends of the 55 central portions 38 of the plates, thereby maintaining the Y-shaped grooves in alignment. Like the 60 previously described embodiment of the invention, the slider illustrated in Figs. 5 and 6 can be moved readily on the rows of fastener elements 65 of the fastener structure in the normal operation of the latter. Should a lateral pull, however, be exerted on the stringers above the slider, the elements will jam against the separating member formed by the central portions 38 of the plates 70 and obstruct movement of the slider in the opening direction in the same manner as has already been described with respect to the preferred form of the invention, until positively moved in such direction by manual operation of the pull tab. 75 It will be noted in the construction illustrated in

Fig. 6 that the forward ends of the outer edge portions of the channel terminate short of the forward end of the central portions 38 which form the separating member instead of extending forward to the front edge of the separating member as is the case in the previously described embodiment. The forward ends, however, are sufficiently spaced from the leg of the channel to enable the jamming action to take place between the elements and the separating member 10 under lateral stresses applied to the stringers above the slider.

I claim:

1. A slider for a separable fastener of the type which includes a pair of stringers provided with 15 interlocking fastener means along their opposed edges, comprising a body portion having a Y-shaped channel therein for receiving the fastener elements, an internal separating means intermediate the diverging arms of said channel and 20 having side surfaces forming the inner walls of such channel arms and adapted to separate the fastener elements of the stringers in the movement of the slider relative to such elements in the opening direction, and fastener element 25 jamming means provided on the inner terminal end of said separating means and positioned at the junction of such channel arms and lying in the path of the engaged ends of the fastener elements in their passage through the central leg of 30 the channel towards said separating means, one of the outer side walls of said channel having two longitudinally separated surface portions and an intermediate connecting portion spaced from a straight line connecting such portions, said line 35 lying between said intermediate portion and said jamming means, the substantially normal distance between said line and said jamming means being less than the length of one of the fastener elements, whereby when a lateral pull is exerted 40 on the fastener above the slider tending to straighten the part of the stringer between the spaced portions of said wall, the outer end of a fastener element will engage with said jamming means to prevent movement of the slider in the 45 opening direction.

2. A slider for a separable fastener of the type which includes a pair of stringers provided with 50 interlocking fastener means along their opposed edges, comprising a body portion having a branched channel therein for receiving the fastener elements, the outer side wall of one of the branches of said channel having two longitudinally spaced portions offering no bar to the 55 passage of the fastener elements through the channel and an intermediate connecting portion spaced from and lying on one side of a straight line connecting such portions, a rigid member spaced from said wall on the opposite side of said line and having a jamming surface portion 60 at the junction of the diverging arms of said channel and disposed in opposed relation to the travel of the fasteners through the central leg of the channel in one direction and being positioned in the slider intermediate the transverse sections 65 thereof containing the spaced portions of said wall, said surface portion of the rigid member being spaced from said wall at a distance greater than the length of the fastener elements and being spaced in a direction substantially normal to 70 the straight line connecting said portions of the wall at a distance not greater than the length of the fastener elements, whereby when a lateral pull is exerted on the fastener above the slider tending to straighten the part of the stringer be- 75

tween such spaced portions of said wall, the outer end of a fastener element will engage with said jamming surface portion of the rigid member to prevent movement of the slider in the opening direction.

3. A slider for a separable fastener of the type which includes a pair of stringers provided with interlocking fastener means along their opposed edges, comprising a body portion having a Y-shaped channel therein for receiving the fastener elements, an internal separating means intermediate the diverging arms of said channel and having a substantially wedge-shaped inner end, the inner terminal end of said separating means forming the junction of said channel arms and lying in the path of the engaged ends of the fastener elements in their passage through the central leg of the channel towards said separating means, the inner ends of each of the outer walls of said channel arms being spaced from the outer end of the central leg of the channel at a

distance less than the distance of the terminal end of the separating means therefrom and each of the outer walls of said channel arms having an intermediate portion connecting the longitudinally separated inner and outer ends thereof and spaced from a straight line connecting such ends, said line lying between such intermediate portion of the wall and the inner terminal end of said separating means, the substantially normal distance between said line and the inner terminal end of said separating means being less than the length of one of the fastener elements, whereby when a lateral pull is exerted on the fastener above the slider tending to straighten the parts of the stringers between such inner and outer ends, the outer end of a fastener element on either stringer will engage under the terminal end of said separating means to prevent movement of the slider in the opening direction.
